DESIGN FOR A CLAMP-AMMETER

Paul P. Huber, Hillside, N. J., and Lurelle Guild, Darien, Conn., assignors to Weston Electrical Instrument Corporation, Newark, N. J., a corporation of New Jersey

Application November 13, 1939, Serial No. 88,244

Term of patent 7 years

To all whom it may concern:

Be it known that we, Paul P. Huber and Lurelle Guild, citizens of the United States, residing at Hillside, county of Union, State of New Jersey, and Darien, county of Fairfield, State of Connecticut, respectively, have invented a new, original, and ornamental Design for a Clamp-Ammeter, of which the following is a specification, reference being had to the accompanying drawing, forming part thereof, and wherein:

Fig. 1 is a front elevation of the clamp-ammeter, showing our new design.

Fig. 2 is a rear elevation of the same; and

Figs. 3 and 4 are side elevations as seen from the left and the right, respectively, of Fig. 1.

We claim:

The ornamental design for a clamp-ammeter, as shown.

PAUL P. HUBER.
LURELLE GUILD.
